UNITED STATES PATENT OFFICE.

PETER FORG, OF SOMERVILLE, MASSACHUSETTS.

CORNER FLUSH-BOLT.

SPECIFICATION forming part of Letters Patent No. 451,474, dated May 5, 1891.

Application filed October 9, 1890. Serial No. 367,492. (No model.)

To all whom it may concern:

Be it known that I, PETER FORG, of Somerville, county of Middlesex, State of Massachusetts, have invented an Improvement in Corner Flush-Bolts, of which the following description, in connection with the accompanying drawings, is a specification, like letters and figures on the drawings representing like parts.

10 This invention has for its object the production of a simple and efficient flush-bolt adapted to be applied to the corner or edge of a closet or other door to be fastened.

15 My improved bolt consists of a shell having substantially right-angled lips or flanges, a substantially circular portion, and a longitudinally-movable bar therein.

20 My improved bolt is slotted at its circular portion to form a spring to hold the bar in the position in which it may be left in the shell.

25 Figure 1 represents two closet-doors, one of which has one of my bolts attached to it; Fig. 2, a cross-section in the line x , and Fig. 3 a vertical section in the line x' .

The case or shell of the bolt, composed of sheet metal, iron, or brass, is bent to leave a nearly circular central part a , with flanges a' a^2 substantially at right angles, so as to em-

brace the corner of the door b , to which it is applied by screws 2 3. This case or shell is 30 slotted at 4 for the passage through it of the usual finger-piece 5, which enters the bolt-bar c .

To keep the bar in the position in which it is left by the finger-piece, I have slotted the 35 shell to leave a spring-tongue 8, which is turned in against the bar.

I claim—

1. The herein-described corner-bolt, consisting of a bar and a case or shell bent to 40 form a substantially circular central portion and having flanges a' a^2 at an angle to each other, substantially as described.

2. A bolt consisting of a bar and a shell bent to form a central circular bar-receiving portion and having flanges a' a^2 at right angles to each other, as described, and slotted in said circular portion to form a spring-finger, substantially as described.

In testimony whereof I have signed my 50 name to this specification in the presence of two subscribing witnesses.

PETER FORG.
